(57) **CLAIM**

The ornamental design for a handheld ultrasound system, as shown and described.

DESCRIPTION

FIG. 1 is a perspective view of a handheld ultrasound system configured in accordance with the present invention;

FIG. 2 is a front view thereof;

FIG. 3 is a back view thereof;

FIG. 4 is a right side view thereof;

FIG. 5 is a left side view thereof;

FIG. 6 is a top view of thereof; and,

FIG. 7 is a bottom view thereof.

The broken lines depict portions of the handheld ultrasound system that form no part of the claimed design; the broken lines form no part of the claimed design.

1 Claim, 4 Drawing Sheets
